US0D1109763S

(12) **United States Design Patent** (10) **Patent No.:** **US D1,109,763 S**
(45) **Date of Patent:** **** Jan. 20, 2026**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Raymond Sepulveda**, Portland, OR (US); **Chun Kin Minor Wong**, Cupertino, CA (US)

(73) Assignee: **Apple Inc.**, Cupertino, CA (US)

(**) Term: **15 Years**

(21) Appl. No.: **29/840,800**

(22) Filed: **Jun. 1, 2022**

Related U.S. Application Data

(63) Continuation of application No. 29/768,265, filed on Jan. 28, 2021, now Pat. No. Des. 955,424, which is a continuation of application No. 29/693,108, filed on May 30, 2019, now Pat. No. Des. 910,710.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines depict a display screen or portion thereof, and form no part of the claimed design. The interior broken lines depict portions of the graphical user interface which form no part of the claimed design.

**1 Claim, 1 Drawing Sheet
(1 of 1 Drawing Sheet(s) Filed in Color)**
